L. L. YOUNG

EXPANSION REAMER

Filed Nov. 22, 1921

Inventor
Luther L. Young,
By
Dwight L. Morris,
Attorney.

UNITED STATES PATENT OFFICE.

LUTHER L. YOUNG, OF SPOKANE, WASHINGTON.

EXPANSION REAMER.

Application filed November 22, 1921. Serial No. 517,057.

To all whom it may concern:

Be it known that I, LUTHER L. YOUNG, a citizen of the United States, residing at Spokane, in the county of Spokane and State of Washington, have invented new and useful Improvements in Expansion Reamers, of which the following is a specification.

This invention relates to expansion reamers and while adapted for any class of work to which a reamer is usually applied, it is particularly designed for use in reaming axially aligned bores such as the wrist pin bearings in pistons.

One of the objects of the invention is the provision of a tapered spindle on which are mounted split cylindrical guide and cutting elements each having an internal taper fitting the tapered spindle, said elements being expanded by forcing them toward the enlarged end of the tapered spindle, the external diameter of said guide and cutting elements being maintained equal throughout their range of expansion.

Another object of the invention is the provision of means cooperating with said spindle and with said guide and cutting elements for adjustably expanding and contracting the latter to change their diameter, said means having a limit stop to prevent expansion of said elements beyond their capacity.

Another object of the invention is the provision of a collar surrounding said spindle between said guide and cutting elements and acting as a thrust member to transmit the force applied to one of said elements by the adjusting means, to the other of said elements, in either direction.

Another object of the invention is to provide a longitudinal groove in said spindle and keys for said guide and cutting elements, fitting said groove, by which said elements are splinably mounted relative to said spindle.

A further object of the invention is to provide a split cutting element having projecting spiral cutting teeth by virtue of which said cutting element will ream a round hole in a bearing or through an aperture provided with a longitudinal groove.

Still another object of the invention is the provision of hollow split guide and cutting elements, the walls of each being thinnest adjacent the split portion thereof and thickest on the side opposite said split por-

tion, said guide and cutting elements being provided with teeth which are proportionately longer as they approach the split portion of the walls of said elements so that the surfaces of said teeth lie in the surface of a cylinder the axis of which is coincident with the axis of rotation of said spindle.

With the above and other objects in view, my invention consists in the improved expansion reamer, illustrated in the accompanying drawings, described in the following specification, and particularly claimed, and in such variations and modifications thereof as will be obvious to those skilled in the art to which my invention relates.

In the drawings accompanying and forming a part of this specification, and wherein the preferred embodiment of my invention is illustrated:

Figure 1 is a side elevation of my improved reamer with a portion thereof shown in section, the guide and cutting elements being expanded.

Figure 2 is a view showing the cutter and guide elements in contracted position.

Figures 3 and 4 are cross sectional views of the cutting and guide elements taken respectively along the lines 3—3 and 4—4 of Figure 2.

Referring in detail to the several figures the numeral 1 represents a spindle having a wrench-hold 2 adjacent the upper end thereof and having a portion 3 gradually tapered downwardly toward its lower end. Mounted on said tapered portion is the guide element 4 and the cutting element 5, each having projecting teeth on its exterior surface, which lie within the surface of a cylinder the axis of which coincides with the axis of rotation of the spindle 1. The guide and cutting elements are each formed with frusto-conical bores of the same pitch as the tapered portion 3 of the spindle so that they fit said spindle when placed thereon. The wall 6 of the guide element 4 is of gradually increasing thickness from a point on its periphery to a point diametrically opposite and of gradually decreasing thickness from the latter to the former point. Similarly, the wall 7 of the cutting element 5 is of gradually increasing thickness from a point on its periphery to a point diametrically opposite and of gradually decreasing thickness from the latter to the former point.

Said walls are split in their thinnest

parts, the varying thickness of said walls serving to render the guide and cutting elements uniformly expansive, circularly, when spread. The guide element 4 is split 5 longitudinally, as shown at 8, and the cutting element is split spirally, as shown at 9. The guide and cutting elements are each provided with a longitudinal internal groove 10 forming guideways for keys 11 and 12, 10 respectively, which keys 11 and 12 are fitted in suitable keyways formed on the surface of the spindle 3 and which permit endwise movement of said elements at the same time preventing rotation thereof relative to said 15 spindle. The end surfaces of said guide and cutting elements are preferably beveled as at 20 and between the inner end surfaces of said elements is arranged a collar 13 which is preferably unsplit and loosely surrounds 20 said spindle, said collar acting as a thrust member to transmit longitudinal force, which may be applied at one end of the cutting element, to the guide element and, vice versa, to transmit force applied to the guide 25 element to the cutting element.

The spindle 1 is threaded as at 14 and 15 at the opposite ends of the tapered portion 3, and upon these threaded portions nuts 16 and 17 are mounted, said nuts having socket 30 portions 21 and 22, respectively, the ends of which are preferably beveled inwardly to receive and engage the beveled outer ends of the guide element 4 and the cutting element 5, respectively. Shoulders 18 and 19, 35 respectively, are formed on the interior of the nuts 16 and 17, respectively, at the point where the threaded portion joins the socket portion. The shoulder 19 of the nut 17 mounted on that end of the tapered portion 40 3 which is of smaller diameter functions as a limit stop to prevent excessive expansion of the guide and cutting members beyond the maximum capacity for which they were designed.

45 In operation the guide and cutting elements are expanded by loosening the nut 16, advancing the nut 17 the required amount, and then tightening back the nut 16 to hold said elements rigid in their new position of 50 adjustment. For contracting said elements the operation is reversed, that is, the nut 17 is backed off, the nut 16 is advanced to make the proper adjustment, and the nut 17 is again tightened. It is not essential that the 55 tapered portion of the spindle 3 be formed in a single taper, a taper in two stages being permissible, the essential requirement being that the taper or tapers shall have the same pitch so that the ratio of the diameter of the 60 guide and cutting elements shall not change through the range of expansion of the reamer.

The guide element 4 is provided with longitudinal teeth and, while preferable, it is 45 not absolutely essential that a key be pro-

vided for this element since it does not act as a cutter and relative rotation between it and the spindle may not be objectionable.

The teeth on the cutting element 5 are spirally arranged so that it may operate in 70 a hole having a longitudinal groove in its surface such as the oil groove often found in bearings. The spiral arrangement of teeth also prevents chatter and ensures the making of a smooth surface. 75

Since the guide and cutting elements have the same diameter at all times, that is to say, since the ratio of their diameters does not change, the device will ream axially aligned 80 holes in perfect alignment, the guide element 85 co-acting with one hole while the cutting element operates within the other.

Obviously, changes in the details of construction may be made without departing 85 from the spirit of the invention and I do not 90 wish to limit myself to any particular form or arrangement of parts.

Having described my invention what I 90 claim as new and desire to secure by Letters Patent, is:—

1. An expansion reamer comprising a tapered spindle, an expansible guide element and an expansible cutting element, each having a tapered bore corresponding in pitch to that of the tapered spindle and fitted for 95 endwise movement thereon, a thrust collar loosely surrounding said spindle and abutting the adjacent ends of said guide and cutting elements and means for applying force to the outer end of one of said elements. 100

2. An expansion reamer comprising a tapered spindle, an expansible guide element and an expansible cutting element each having a tapered bore corresponding in pitch to that of the tapered spindle, and fitted for 105 endwise movement thereon, a thrust collar loosely surrounding said spindle and abutting the adjacent ends of said guide and cutting elements and means for selectively applying force to the outer end of the guide element or the cutting element for moving said elements endwise in either direction relative to said spindle.

3. An expansion reamer, comprising a tapered spindle, a train of contacting elements mounted on said spindle comprising an expansible guide element, and an expansible cutting element of the same outside diameter, each having a tapered bore corresponding in pitch to said tapered spindle, and a collar arranged intermediate the two, means for adjustably moving said train of 115 elements in either direction relative to said tapered spindle and means for securing them in any position of adjustment. 120

4. An expansible cutting element comprising a cylindrical body provided with a central bore and with radially extending spiral cutting teeth, the outer surface of said cutting teeth lying in the surface of a cylinder 130

the axis of which is coincident with the axis of said central bore, said teeth being of progressively different depth forming a supporting wall which is thinner on one side than on the other, said wall being split spirally at its thinnest portion.

5. An expandible cutting element comprising a cylindrical body provided with a central bore and with radially extending 10 spiral cutting teeth, the outer surface of said cutting teeth lying in the surface of a cylinder the axis of which is coincident with the axis of said central bore, said teeth being of progressively different depth forming 15 a supporting wall which is thinner on one side than on the other, said wall being split spirally at its thinnest portion and a keyway being provided in its thickest portion.

6. An expansion reamer comprising a 20 tapered spindle having a wrench hold at its upper end, the tapered portion of said spindle being provided with a longitudinal spline groove, an expandible guide element and an expandible cutting element each having 25 a frusto-conical bore corresponding in pitch to the tapered portion of said spindle and fitted thereon, each of said elements being provided with an internally projecting spline registering with said spline 30 groove, a thrust collar surrounding said spindle intermediate said guide and cutting elements, and a nut threaded on the lower end of said spindle and engaging the outer end of said cutting element.

35 7. An expansion reamer comprising a spindle having a tapered portion and a wrench hold at its upper end, said spindle being threaded at both ends adjacent said

tapered portion, an expandible guide element and an expandible cutting element, 40 both splinably mounted on the tapered portion of said spindle and separated by a thrust collar, a nut threadedly engaging the upper threaded portion of said spindle and contacting with the outer end of said 45 guide element and a nut engaging the lower threaded end of said spindle and contacting with the outer end of said cutting element, said nut being provided with an internal shoulder engaging with a portion of said 50 spindle to limit the expansion of said expandible element.

8. An expansion reamer comprising a spindle having a tapered portion, a guide element having an internal taper of the same pitch as said tapered portion and mounted thereon, said guide element being split longitudinally and provided with longitudinally arranged radially projecting teeth, a cutting element having a tapered bore corresponding in pitch to the tapered portion of said spindle and mounted thereon, said cutting element being spirally split and having spirally arranged radially projecting teeth, a thrust collar loosely surrounding 60 said tapered spindle contacting with the inner adjacent ends of said guide and cutting elements, a nut engaging the smaller end of said tapered spindle for forcing said cutting and guide elements toward the larger end of 65 said spindle and means to limit the longitudinal movement of said nut.

In testimony whereof I have hereunto set my hand.

LUTHER L. YOUNG.
